UNITED STATES PATENT OFFICE.

EDWARD A. MAINGUET, OF EVANGELINE, LOUISIANA.

HARVESTER.

SPECIFICATION forming part of Letters Patent No. 739,690, dated September 22, 1903.

Application filed July 20, 1901. Serial No. 69,044. (No model.)

To all whom it may concern:

Be it known that I, EDWARD A. MAINGUET, a citizen of the United States, and a resident of Evangeline, in the parish of Acadia and State of Louisiana, have made certain new and useful Improvements in Harvesters, of which the following is a specification.

My invention is an improvement in harvesters, and has for an object, among others, to simplify and improve the construction of the apparatus, as will be more fully described hereinafter; and the invention consists in certain novel constructions and combinations of parts, as will be hereinafter described and claimed.

In the drawings, Figure 1 is a vertical longitudinal section on about line 1 1 of Fig. 2. Fig. 2 is a top plan view of a portion of a harvester embodying my improvements, and Fig. 3 is a detail top plan view illustrating the connection between the cutter-bar and the packer whereby the latter is driven from the cutter-bar by a pitman connected to the cutter-bar.

The cutter-bar A is supported in suitable guides B in advance of the endless carrier C, as shown in Fig. 2. This cutter-bar A is reciprocated by means of the lever D, which extends between the upper and lower runs of the carrier C, is pivoted at D' between its ends at a point between the runs of the carrier C, is connected at its front end by the pitmen D² with the cutter-bar A, such pitmen being pivoted at their adjacent ends to the forward end of the lever D and extending thence outwardly in opposite directions and pivoted at D³ to the cutter-bar at the opposite ends of the latter, and means are provided at D⁴ for reciprocating the rear end of the lever D so its front end will be caused to operate the cutter-bar, as desired.

The carrier C is composed of a series of comparatively narrow belts C', each provided with projecting teeth or bars C² and extending side by side and around the outer and inner rollers E and E', one of which may be driven in any suitable manner to cause the carrier-belts to travel in the direction indicated by the arrows in Fig. 1. The roller E' is provided between the carrier-belts C' with grooves e', extending circumferentially and arranged to receive the points f at the ends

of the spring-plates F and F', which spring-plates constitute the base of the packer, as will be more fully described. It will be noticed that the outer spring-plates F of the packer-base differ slightly from the plates F', being in the form of one-half of said plates F, as best shown in Fig. 2. These plates F and F' may be integral and formed by slotting a plate F² at F³ from one end thereof to form the separate spring-plates and also to provide ways by means of the slots F³ for the teeth of the packer. This packer G is arranged a short distance from the inner roller E', providing a space between the packer and the said roller E', which space is spanned by the plates F and F', which latter are arched slightly upward within said space, as shown in Fig. 1, and curve gradually toward their extremities, where they are provided with the tongues f, which project within the grooves e' of the roller E', as shown and before described.

The packer G comprises an endless apron G', provided with teeth G² and extending around suitable pulleys H and I, the pulley H being the elevated guide-pulley and the pulleys I being both guide and drive pulleys and being connected by a belt I', one of said pulleys I being provided with a crank I², which is connected by a pitman I³ with the inner end of the cutter-bar, so such cutter-bar will serve to operate the packer, as will be understood from Figs. 1 and 2. It will be understood that the binding mechanism may be constructed in any ordinary manner and applied to the harvester in the usual or other desired manner and be connected with and driven by the lever D, and as the construction of said binder forms no part of the present invention it does not seem necessary to illustrate it herein. It will be noticed particularly that the carrier C and the packer-springs are arranged in alinement, that the packer-base, being in a straight line with the middle of the rollers E E', is constructed to receive the grain directly from the carrier C by means of upwardly curved or arched portions of its spring-plates, and that the lever extending between the runs of the carrier C is arranged to operate the cutter-bar and the packer and is so disposed that it is not likely to become clogged by the grain. The bars

- F^4 having an inclination, as shown in Fig. 1, will force the grain to leave the packer and stay on the plate F^2 and pass thereon to the binding mechanism.
- 5 As will be understood from the drawings and foregoing description, the lever D is in practice connected with and drives the several moving parts of the machine. The pulley H may operate as a fly-wheel, or, if necessary or desirable, a separate fly-wheel may be provided to insure the movement of the crank past the center. In operation to insure the movement of the parts in the proper direction in starting the machine motion in the 15 desired direction may be imparted by hand to the packer or other moving part of the apparatus. It will be understood that in thus giving the proper direction to the packer in starting the machine the spokes of the wheel 20 H, such as shown in Fig. 1, may be grasped in the hand of the operator, and the said wheel may be turned in the proper direction to start the packer as the machine is started.
- Having thus described my invention, what 25 I claim as new, and desire to secure by Letters Patent, is—
1. The improvement in harvesters herein described comprising the packer having the endless apron, the guide-pulley and the opposite guide and drive pulleys one of which is provided with a crank, the belt connecting the guide-pulleys, the carrier, the inner and outer rollers therefor, the inner roller being provided with annular grooves spaced apart 30 and the carrier being composed of a series of belts arranged between the said grooves, the packer-base composed of a plurality of spring-plates provided at their ends with tongues entering the grooves of the carrier-roller and 35 having their portions adjoining said tongues gradually curved or bowed upwardly, the cutter-bar, a pitman connecting the cutter-bar with the crank-arm of the drive-pulley of the packer, the lever extended between the 40 runs of the belt, the pitmen connected with the forward end of the lever and extending thence in opposite directions and connected with the cutter-bar, and guides for the cutter-bar substantially as set forth.
- 45 2. In a harvester substantially as described the combination with the packer and the endless carrier composed of a series of belts spaced apart and the inner and outer rollers for said belts, the inner roller being provided adjacent to the belts with annular grooves and the packer-base having a series of spring-plates extending beneath the packer and across the space between the packer and the inner roller of the carrier and provided at 50
- their extremities with tongues entering the 60 grooves of the carrier-roller substantially as set forth.
3. In a harvester substantially as described the combination of the carrier composed of a series of separated belts, the inner and outer 65 rollers for said belts, the inner roller being provided between the belts with annular grooves, the packer, and the packer-base below the packer and having a series of spring-plates whose extremities operate within the 70 grooves of the packer-rollers, substantially as set forth.
4. In a harvester substantially as described, the combination of the endless carrier, the packer having its apron provided with teeth, 75 and the packer-base below the packer and composed of a plate slotted from one end forming the spring-plates and ways for the teeth of the packer-apron, said spring-plates being extended across the space between the 80 packer and the carrier substantially as set forth.
5. A harvester substantially as described comprising a cutting apparatus, the carrier in rear thereof and composed of the separate 85 belts extending side by side and spaced apart, the packer, and the packer-base arranged beneath the packer and composed of a series of spring-plates extending in alignment with the space between the belts of the 90 carrier approximately in a horizontal plane, substantially as set forth.
6. In a harvester substantially as described the combination of the carrier, the cutter-bar extending in advance of the carrier, the packer 95 comprising the apron, and guide and drive pulleys, one of the latter having a crank, a pitman connecting such crank with the cutter-bar, means for operating the cutter-bar and the packer-base, substantially as set 100 forth.
7. In a harvester substantially as described the combination of the carrier composed of a series of belts extending side by side, rollers 105 supporting said belts, one of the rollers being provided between the belts with annular grooves, the packer, and the packer-base composed of spring-plates extending in alignment with the space between the carrier-belts and having their ends tapered and terminating in tongues entering the grooves in the roller supporting the carrier-belts substantially as set forth.
